(57) **CLAIM**

The ornamental design for a headlamp, as shown and described.

DESCRIPTION

FIG. 1 is a perspective view of the headlamp.

FIG. 2 is a front elevational view of the headlamp of FIG. 1.

FIG. 3 is a side elevational view of the headlamp of FIG. 1 with the other side being the same.

FIG. 4 is a top plan view of the headlamp of FIG. 1 with the bottom plan view being the same.

FIG. 5 is a back elevational view of the headlamp of FIG. 1.

FIG. 6 is a perspective view of an alternate design for the headlamp.

FIG. 7 is a front elevational view of the headlamp of FIG. 6.

FIG. 8 is a side elevational view of the headlamp of FIG. 6 with the other side being the same.

FIG. 9 is a top plan view of the headlamp of FIG. 6 with the bottom plan view being the same; and,

FIG. 10 is a back elevational view of the headlamp of FIG. 6.

The broken lines depict portions of the headlamp that form no part of the claimed design.

1 Claim, 10 Drawing Sheets
